ROY W. JOHNSON, OF MILWAUKEE, WISCONSIN, ASSIGNOR, BY MESNE ASSIGNMENTS,
TO THE TIME-O-STAT CONTROLS COMPANY, A CORPORATION OF MARYLAND

TIME-CONTROLLED APPARATUS

Application filed August 12, 1926. Serial No. 128,773.

This invention relates to improvements in time-controlled apparatus including a timing unit and a unit controlled thereby, and more particularly to the construction and arrangement of the means providing an operating connection between such units.

The various gas appliances of the type used in the home, such as water heaters, incinerators, driers, etc. are now commonly controlled by a timing unit or mechanism operable to automatically cause closing of the gas supply valve after the burner of the appliance has operated a predetermined period of time as determined by the setting of the timing unit. The present improvement contemplates the provision of apparatus of the character referred to wherein the timing unit is directly and positively connected to the unit or member to be controlled by a plurality of inter-connected rigid members or links, the connecting links being completely enclosed and protected.

Another object is to provide improved apparatus of the character referred to for controlling a valve and wherein the operating parts of the timing unit are connected directly to the valve by means of a rigid and positive connection.

Another object is to provide improved apparatus of the character referred to which is simple and compact in construction, positive in operation, and wherein the connecting parts between the timing unit and the member or unit to be controlled are connected and guided in such manner that they provide at all times a direct and positive connection between the timing unit and the member controlled thereby.

Other objects and advantages will hereinafter appear.

For the purpose of illustrating the invention one embodiment thereof is shown in the drawings, in which

Figure 1 is a side elevational view, showing the improved apparatus applied to an incinerator of the type adapted for use in the home; and

Fig. 2 is a central vertical sectional view through the improved apparatus.

The casing or gas supply connection 10

for the lift valve 11 is connected as shown in the gas line 12 leading to the burner pipe 13 of an incinerator, designated generally by the reference numeral 14, valve 11 being arranged to seat with the pressure and provided with the stem 15 and urged at all times to closed position by the spring 16. The timing unit is supported and enclosed in a casing 17 secured to the incinerator or other appliance by the screws 18 and connected to the valve casing by the nipple 19.

A manually-operable disk 20 is fixed on the shaft 21 journaled in casing 17 and provided with the laterally extending lug 22 arranged to catch back of the shoulder 23 of a latch 24 upon counter-clockwise movement to the position shown, the latch being pivotally mounted on the pin 25 and urged into and held in latching position by the spring 26.

The timing unit is provided with suitable clockworks including a main spring 27 mounted on the shaft 28 to which is fixed an arm or crank 29 connected to latch 24 through the member 30, a pin 31 being fixed in arm 29 and arranged to slide freely in a longitudinal slot 32 in member 30 whereby counter-clockwise rotation of arm 29 is permitted independently of an accompanying movement of latch 24. The pin 31 is arranged to engage the upper end of slot 32 when arm 29 is rotated clockwise to a predetermined position to pull upwardly on member 30 and cause clockwise movement of latch 24 about pin 25 out of latching engagement with lug 22. The disk 20 is connected to valve 11 through the link 33 and plunger 34 pivotally connected at their adjacent ends by the pin 35, the upper end of link 33 being pivotally connected at 36 to disk 20.

As shown, plunger 34 extends into and is guided by nipple 19 for axial movement, the plunger being supported in alignment with the valve stem 15 and engaging the latter so that upon counter-clockwise movement of shaft 21 the plunger is moved axially to open valve 11 against the action of spring 16. Lug 22 is arranged to catch back of shoulder 23 of the latch when disk 20 has been rotated to the position shown, in which position of the disk link 33 and plunger 34 are almost

in alignment with each other. The clock mechanism is set by the handle or crank 37 fixed on shaft 28 and provided with the pointer 38 arranged to move over the dial 39 on casing 17 and to engage the stops 40 and 41 for the purpose hereinafter explained. The shaft 21 and disk 20 carried thereby are rotated by the handle or crank 42 fixed on shaft 21.

10 The timing unit just described, which may be of any suitable construction, is more fully shown and described in the patent to Gauger et al. 1,652,524, December 13, 1927, and for this reason has only been shown and described with sufficient clearness to enable those skilled in the art to understand the manner in which such a suit may be embodied in the present improved apparatus.

When it is desired to operate the gas burner for a given period of time, such as thirty minutes, for example, the crank 37 is rotated in a counter-clockwise direction to the point "30" on dial 39, this movement of the crank operating to wind up the main spring 27 of the clockworks and permitting operation thereof to cause gradual clockwise movement of the pointer 38 back into engagement with lug 40, after a period of thirty minutes. This setting movement of the clockworks also causes a corresponding downward movement of member 30 to permit latch 24 to drop into latching position so that upon subsequent counter-clockwise movement of crank 42 and disk 20, fixed for rotation with the latter, lug 32 will catch back of shoulder 23 of the latch whereby the link 33 and plunger 34 are held in the position shown for the period of time elapsing until latch 24 is raised out of latching or holding position upon engagement of pin 31 with the upper end of slot 32 to permit closing of valve 11 by the action of spring 16.

10 Suitable packing 43 may be provided in nipple 19 to insure against leakage of gas from casing 10 into casing 17 by way of the nipple, this packing being held compressed by a spring 44 compressed between the packing, as shown, and a shoulder 45 with which plunger 34 is provided.

The lug 41 limits counter-clockwise setting movement of shaft 28, and when the latter is rotated to engage dial 38 with this lug the timing unit is set to permit operation of the burner for the maximum period of time.

15 While the improved apparatus has been shown applied to an incinerator, it will be understood of course that the invention is of much broader adaptation and that the improved apparatus may be applied to other appliances as well, such as water heaters, driers, etc. Furthermore, the member or unit to be controlled may be of a different type than the valve shown, such as an electric switch, for example.

20 Various changes may be made such as in

the size, shape and arrangement of the parts without departing from the spirit of the invention or the scope of the claims.

The invention claimed is:

1. In a device for use with a gas appliance 70 having a valve casing and a spring closed valve therein, the combination of a nipple secured to the valve casing, a plunger slidable in the nipple and engageable with the valve for opening the same, a casing surmounting 75 the nipple, a disk rotatably mounted in the casing and a link eccentrically connected with the disk and pivoted to the plunger.

2. A device for use with a gas appliance 80 having a valve, a plunger cooperable with and controlling the valve, a casing, a manually operable shaft mounted in said casing, an element fixed to rotate with the shaft, a link eccentrically connected to said element and pivotally connected to the plunger, a 85 trigger pivotally mounted in the casing and cooperable with said element for holding the same against movement and a valve spring normally urging said valve to closed position and exerting torque upon said element 90 through said link and plunger to cause rotation of said element upon release of said trigger.

3. In a device of the class described having 95 a valve with a reciprocable valve stem thereon, a casing, a setable time device in said casing, a trigger operated by said time device and a rotatably mounted element controlled by said trigger, the combination of a plunger 100 for actuating said valve stem, a guide mounted on said valve and maintaining said plunger in a position to reciprocate with said valve stem and a link connected to said plunger and eccentrically connected to said rotatably mounted element, said link being 105 operable to hold said plunger and hence said valve stem in a given position upon said trigger and time device being set to hold said rotatably mounted element in a given position.

110 In witness whereof, I hereto affix my signature.

ROY W. JOHNSON.
